UNITED STATES PATENT OFFICE.

CHARLES DENVER BOWERS, OF NEW YORK, N. Y.

ADVERTISING DEVICE.

1,366,866.

Specification of Letters Patent. Patented Jan. 25, 1921.

Application filed August 2, 1920. Serial No. 400,743.

To all whom it may concern:

Be it known that I, CHARLES D. BOWERS, a citizen of the United States, and a resident of the city of New York, borough of 5 Manhattan, in the county and State of New York, 318 West 57th street, have invented a new and Improved Advertising Device, of which the following is a full, clear, and exact description.

10 This invention relates to display apparatus or advertising devices and has particular reference to a movable structure embodying elements so carried by the movable structure as to possess relative movement in 15 another direction, there being provided letters or other characters and associated windows or openings so related as to produce a multiplicity of variable inscriptions as a result of continued movement or interchange 20 of position of the various parts between which there is relative movement.

More specifically the invention has for an object provision of a movable device simulating a dutch windmill, upon each arm or 25 blade of which are pivoted a series of disks, each disk bearing a plurality of characters adapted to be brought into display position in succession as a result of the revolution of the disk with the arm around the 30 axis of the wheel and the simultaneous rotation of each disk on its own axis.

Another object of the invention is to provide a rotatable member upon which are carried a series of members having various 35 characters on their periphery, the character members being caused to revolve around the axis of the rotatable member as a result of such rotation, but with means to hold the character members from actual rotation 40 around their own axes, means being provided in connection with said character members to cause different portions thereof and consequently different characters carried thereby to be brought successively into 45 view as a result of the rotation of the first mentioned member.

With the foregoing and other objects in view the invention consists in the arrangement and combination of parts hereinafter 50 described and claimed, and while the invention is not restricted to the exact details of construction disclosed or suggested herein, still for the purpose of illustrating a practical embodiment thereof reference is

had to the accompanying drawings, in which 55 like reference characters designate the same parts in the several views, and in which

Figure 1 is a front elevation of a device embodying the principal features of my invention.

Fig. 2 is a horizontal section on the line 60 2-2 of Fig. 1, the parts being on an enlarged scale.

Referring now more specifically to the drawings I show a device comprising a support 10 in the nature of the body of a windmill having a door 11 and a window 12. Journaled in the upper portion of the mill is a horizontal shaft 13 which may be caused to rotate slowly by any suitable means such 65 as a motor M located at any desired place either inside or outside of the mill according to the display effect desired. That is to say if it is intended for the wind wheel to appear to be caused to rotate by the wind 70 and independent of any other movable parts the motor would be located either within the mill or at the rear thereof, but as indicated in the drawings it would appear that the wind wheel, due to the rotation thereof from 75 the wind, would cause the rotation of the motor as a generator.

The wind wheel above referred to is shown as comprising a series of radial arms or wings 14 all rigidly connected to the hub 85 15 and hence caused to rotate simultaneously upon and with the shaft 13. The direction of rotation may be assumed to be in the direction of the large arrow or clockwise.

As shown best in Fig. 2 each wing is composed of front and rear parallel panels within the space 16 of which are journaled a series, shown as four in number, of character members such as disks 17. Each of 95 these disks is journaled at 18 for free rotation in the space aforesaid, but normally is held from rotation by some suitable means such as a weight 19 attached to the lower edge thereof so that under ordinary conditions the disks 17 do not rotate actually except that the relative movement between the disks and the wing carrying them is in effect a counter clockwise rotation.

Carried by each of the disks or character 105 members 17 are a plurality of characters such as letters of a variable nature the same being located at any desired distance from

the centers of the disks, although they are indicated as being substantially concentric or located at equal distances from the centers.

5 The front panels of the wings are each provided with a series of openings or windows 20 located in a uniform manner with respect to the disk centers, the openings being shown as being located beyond the disk centers 18 from the shaft 13 and the arrangement being such that the letters or characters on the disks are brought to view in succession through the windows as a result of the rotation of the wheel or the several wings around the axis of the shaft 13. The number of characters or letters on each disk may be four as shown or more or less depending upon the rapidity of interchange desired or the number of different display 20 words or the like to be displayed by each wing as it makes a rotation. The wing at the right side of Fig. 1, for the best understanding of the invention, is shown as having the front panel removed, so that each 25 of the disks 17 is shown carrying four variable characters or letters, correspondingly located letters constituting a series and arranged as indicated but spelling words in succession. Assuming therefore that the device or machine is intended for advertising 30 dairy products the four series of letters on one of the arms may spell in succession Milk, Food, Good, and Rich, while the wing is passing the four quarters of its position 35 while rotating around the axis of the shaft 13, these several words or series of letters being displayed in succession through the same series of windows 20. Obviously all 40 of the wings might have the character members so arranged as to display in succession the same words or in any other order, but preferably all of the words throughout the entire system are different and may be either substantives naming the various commodities to be advertised, or may be words descriptive of the character or quality of such commodities. It is to be noted also that the 45 rear panels may be provided with windows 20' through which characters that may be carried on the opposite side of the disks may be viewed from the other side of the wheel. It will be noted also that the device may be utilized as a mechanical toy, the wheel being 50 adapted to be rotated by flowing sand or

any other suitable actuating means not 55 shown.

I claim:

1. The combination with a movable member and means to cause the movement thereof in a predetermined path, of a character member connected to and movable with the movable member and between which there is relative movement due to the movement of the first member, a plurality of characters carried by the character member, and means 60 serving to present the characters in succession to view as a result of the movement of the movable member in connection with the relative movement between the character member and the movable member. 70

2. In a display device, the combination with a member and means to cause rotation thereof around a fixed axis, a series of character members connected to the movable member and caused by the rotation thereof 75 to revolve around said axis, and means acting upon the character members to hold them from actual rotation while they are revolving.

3. A device as set forth in claim 2 in which the character members which carry a plurality of characters, corresponding characters of the several characters constituting series calculated to spell different words in succession, and means to cause the display 85 of the several words in succession coincident with the rotation of the first mentioned member. 80

4. In a display device, the combination with a rotatable wheel comprising a series 90 of wings and means to cause the rotation of the wings around the axis of the wheel, of a series of character members pivoted upon each wing, each character member bearing a plurality of characters, correspondingly 95 arranged characters of the several character members being calculated to be legible simultaneously and for a single purpose, and means to cause a relative change of position between the wing and all of the character members simultaneously so as to produce a change of display, the last mentioned means comprising a weight carried by each character member and serving to hold a definite portion thereof downward irrespective of 105 any other movements of the device. 100

CHARLES DENVER BOWERS.
